UNITED STATES PATENT OFFICE.

LAURITZ HANS LARSEN, OF CHARLOTTE, NORTH CAROLINA, ASSIGNOR OF FORTY-NINE PER CENT. TO W. W. WATT, OF CHARLOTTE, NORTH CAROLINA.

CLOSET-VALVE.

1,369,344.

Specification of Letters Patent. Patented Feb. 22, 1921.

Application filed August 27, 1919. Serial No. 320,185.

To all whom it may concern:

Be it known that I, LAURITZ H. LARSEN, a subject of the King of Denmark, residing at Charlotte, in the county of Mecklenburg 5 and State of North Carolina, have invented a new and useful Closet-Valve, of which the following is a specification.

The device forming the subject matter of this application is a siphon for a flush tank, 10 and the invention aims to provide novel means for starting the action of the siphon.

It is within the province of the disclosure to improve generally and to enhance the utility of devices of that type to which the 15 invention appertains.

With the above and other objects in view, which will appear as the description proceeds, the invention resides in the combination and arrangement of parts and in the 20 details of construction hereinafter described and claimed, it being understood that, within the scope of what is claimed, changes in the precise embodiment of the invention shown can be made without departing from 25 the spirit of the invention.

In the accompanying drawings:—

Figure 1 shows in vertical section, a portion of a flush tank embodying the improvements hereinafter claimed; Fig. 2 is a top 30 plan of the valve disk; Fig. 3 is an elevation of the valve disk; Fig. 4 is a plan of the head wherewith the valve disk coacts; Fig. 5 is an elevation of the head; Fig. 6 is a top plan showing a portion of a flush tank 35 wherein the device forming the subject matter of this application has been embodied; and Fig. 7 is a cross section taken approximately on the line 7—7 of Fig. 1.

The numeral 1 denotes a flush tank to 40 which water is supplied through a pipe 2. As is common in devices of this kind, the flow of the water through the pipe 2 is controlled by a float-actuated valve, but since the float-actuated valve is a common and 45 well known construction, it is alluded to briefly, without specific delineation in the drawings.

The numeral 3 denotes, generally, a siphon, including an outlet leg 4 and an inlet 50 leg 5, the leg 5 terminating at its lower end in a cylindrical enlargement 6, spaced from the bottom of the tank 1. The outlet leg 4 is secured in any desired way, as shown at 7, to the bottom of the tank 1.

55 The inlet leg 5 carries a guide 8, and there

is an opening 9 in the top of the enlargement 6, a cup 10 being formed about the opening 9, the cup preferably being integral with the top of the enlargement 6 and the inlet leg 5. Internally, the enlargement is 60 supplied with stops 11.

A plunger 12 is mounted to reciprocate in the guide 8 and in the opening 9, the plunger being operated from a convenient point by any suitable means (not shown). The 65 lower end of the plunger 12 is secured at 14 to the hub 15 of a head 16 having a close sliding fit in the enlargement 6, the head 16 preferably being in the form of a spider. The numeral 17 denotes a valve, in the form 70 of a disk, adapted to rest on the head 6 and serving as a closure for the openings in the head, the valve having a neck 18 receiving the plunger 12, the valve 17 thus being mounted to slide on the plunger.

When the plunger 12 is raised, the head 16 75 will be raised, along with the valve 17. Water in the enlargement 6 and in the inlet leg 5 will be lifted and will pass over into the outlet leg 4, the flow through the siphon 80 being started in this way. The stops 11 limit the upward movement of the head 16 so that the head 16 cannot move upwardly, along with the valve 17, to an extent sufficient to cut off the flow to the inlet leg 5. 85 When the flow through the siphon 3 has been started as above described, the water in the tank 1 passes upwardly through the enlargement 6 and the inlet leg 5, the water flowing downwardly through the outlet leg 90 4, until the tank is empty. As the water flows through the siphon 3 in the way above described, the valve 17 rises, responsive to the flowing water, and permits the water to pass through the siphon, the valve clearing 95 the stops 6. When the plunger 12 is released, the same moves downwardly, along with the head 16, and when the water has flowed through the siphon 3, until the siphon sucks air through the lower end of 100 the enlargement 6, the valve 17 moves downwardly on the plunger 12 and seats on the head 16, under the weight of the water in the inlet leg 5. The cup 10 is normally filled with water and prevents the entrance of air 105 into the siphon 3 by way of the opening 9.

Having thus described the invention, what is claimed is:—

In a device of the class described, a flush tank; a siphon having an outlet leg dis- 110

charging from the tank and including an inlet leg receiving the contents of the tank, the inlet leg comprising a lower enlargement and an upper reduced portion, the enlargement having an opening in its top; a cup formed integrally with the enlargement and the reduced portion, at the point of juncture therebetween, and extended around the opening, the cup constituting a water seal for the opening and constituting a reinforcement uniting the enlargement and the reduced portion of the inlet leg; a plun-

ger slidable in the opening; a head secured to the plunger and fitting slidably in the enlargement, the head having an opening; and a valve slidable on the plunger, the valve controlling the opening in the head.

In testimony that I claim the foregoing as my own, I have hereto affixed my signature in the presence of two witnesses.

LAURITZ HANS LARSEN.
